UNITED STATES PATENT OFFICE

128,587

DESIGN FOR A DRESS

Michael M. Levine, New York, N. Y.

Application June 28, 1941, Serial No. 101,788

Term of patent 3½ years

To all whom it may concern:

Be it known that I, Michael M. Levine, a citizen of the United States of America, residing in New York city, county of New York, and State of New York, have invented a new, original, and ornamental Design for a dress, of which the following is a specification, reference being had to the accompanying drawing, forming part thereof, wherein,

I claim:

The ornamental design for a dress, substantially as shown.

MICHAEL M. LEVINE.
